SWING

Henry C. Kregger, Compton, Calif.

Application February 24, 1950, Serial No. 8,107

Term of patent 14 years

(Cl. D15—8)

To all whom it may concern:

Be it known, that I, Henry C. Kregger, a citizen of the United States, residing at Compton, in the county of Los Angeles and State of California, have invented a new, original, and ornamental Design for a Swing, of which the following is a specification; reference being made to the accompanying drawing, forming a part thereof.

Figure 1 is a side elevational view of a swing, showing my new design;

Figure 2 is a top plan view;

Figure 3 is a front elevational view.

The opposite side of the swing is similar to that shown.

I claim:

The ornamental design for a swing, as shown and described.

HENRY C. KREGGER.
